(57) **CLAIM**

I claim the ornamental design for the dish drainer, as shown and described.

DESCRIPTION

FIG. 1 is a front view of a dish drainer having an ornamental sheet according to the present application;

FIG. 2 is a rear view of a dish drainer having the ornamental sheet according to the present application;

FIG. 3 is a left view of the dish drainer having the ornamental sheet according to the present application;

FIG. 4 is a right view of the dish drainer having the ornamental sheet according to the present application;

FIG. 5 is a top view of the dish drainer having the ornamental sheet according to the present application;

FIG. 6 is a top view of the dish drainer without the ornamental sheet according to the present application;

FIG. 7 is a bottom view of the dish drainer according to the present application;

FIG. 8 is a perspective view of the dish drainer having the ornamental sheet according to the present application;

FIG. 9 is a perspective view of the dish drainer without the ornamental sheet according to the present application; and,

FIG. 10 is an exploded view of FIG. 8. The ornamental sheet is shown removed and is shown in two positions.
